UNITED STATES PATENT OFFICE.

JAMES EDWARD WILSON, OF ELDORADO, ILLINOIS.

SLIDE-RAIL HOLDER.

1,376,128.

Specification of Letters Patent. Patented Apr. 26, 1921.

Application filed May 21, 1920. Serial No. 383,168.

To all whom it may concern:

Be it known that I, JAMES E. WILSON, citizen of the United States, residing at Eldorado, in the county of Saline and State 5 of Illinois, have invented a new and useful Slide-Rail Holder, of which the following is a specification.

This invention relates to holders for extensible mine rails.

10 The object is to provide a device for temporarily holding in position a pair of rails laid alongside of and loosely applied to the ends of the fixed laid rails with the heads of the loose rails engaging the webs of the 15 fixed rails beneath the heads of the latter, the loose rails being adapted to be projected more or less beyond the fixed rails, and the holding device being temporarily secured to an intervening tie.

20 A full and complete understanding of the invention may be obtained from the following detailed description taken in connection with the accompanying drawing forming part of this specification, it being understood that while the drawing shows a 25 practical form of the invention, the latter is not confined to any strict conformity therewith, but may be changed and modified, so long as such changes and modifications mark no material departure from the 30 salient features of the invention.

In the drawing, in which similar reference characters designate corresponding parts throughout the several figures;

35 Figure 1 is a perspective view of the end portions of a permanent mine track and showing the improved holder in position to support a pair of temporary rails for extending the said track;

40 Fig. 2 is a detail plan view, on an enlarged scale, of one side of the track;

Fig. 3 is a transverse sectional view of the same;

45 Fig. 4 is a longitudinal sectional view of the abutting ends of the temporary rails and showing the device in engagement therewith and its detachable connection with the tie;

50 Fig. 5 is a detail perspective view of one of the temporary rail holders.

The usual practice in mines is to extend the car track as close to the workable coal or other material as it is possible to do by the use of full length rails. The mine car, 55 however, must be run within a reasonable distance of the mined coal in order that the

miner may readily shovel the same into said car, and for this purpose it is customary to extend the track by short length extension rails temporarily laid in place in longitudinal alinement with the permanent rails and adapted to receive the wheels of the car, and extended sufficiently to carry the car the required distance to reach the mined coal. It has been found expedient 60 to lay these temporary rails on their sides and within or between the permanent rails, with their treads fitting beneath the head of the latter and bearing against the inner faces of the webs of the same and their 65 bases opposed to each other. The wheels of the mine car readily roll off the ends of the permanent rails and onto the upturned sides of the heads of the temporary extension rails, the flanges of the wheels finding their 70 necessary path between the head and the base of the latter. In like manner, after the coal has been cleaned up and carried away by the car or cars, the extension rails may be used to carry the mining machine 75 up to a position to operate on the coal.

The device of the present invention is designed to hold the outer or free ends of the temporary extension rails and to maintain them in spaced relation and in alinement 85 with the permanent rails, and to hold a second pair of extension rails when it is found necessary to use the same in order to reach the work with the car or machine and when it is not desired to place in position the permanent rails.

As shown in Fig. 1 of the drawing, the permanent rails 1 have their terminals secured to a tie 2 by the usual spikes and are of the usual formation having the base, the 90 head and the connecting web.

A pair of slide or extension rails 2, similar in construction to the aforesaid permanent rails 1, are adapted to be fitted between the rails 1 with the head 4 thereof 100 located beneath the overhanging shoulder of the head of the permanent rail, and the base flange 5 standing on edge and resting on the ties 2 which throws the web 6 of the slide rail slightly at an incline, with the 105 lower face of the head of the temporary rail resting on the upper face of the inner base flange of the permanent rail.

By the use of ordinary spikes 7 partially driven in the last tie 2 located at the ends 110 of the rails 1, the extension rails 3 may be slid out the required distance, with relation

to the former, and the two rails may be held in their proper relation to each other to receive and support the wheels of the car. (Not shown).

5 It is to be understood that the rails 3 may be of any desired length, and that the ties for the same are located in the usual manner.

10 The holding device comprises a pair of oppositely disposed heavy sheet metal couplings or sleeves 8 adapted to partially surround the extension rails 3, and to be temporarily secured to a tie 2, and having connecting means for holding them in the 15 proper spaced relation.

The couplings or sleeves 8 each comprise a base portion 9 adapted to rest upon the tie 2 and formed integrally along one edge with an upstanding wall 10, having an inwardly directed wall 11 adapted to fit the tread and upper side face respectively of the head 4 of the extension rail, the said wall 11 having a downwardly or inwardly directed marginal flange 12 adapted to fit the 25 upper shoulder of the extension rail head 4.

At the opposite or inner edge of the base 30 9 an integral upstanding wall 13 is provided which is adapted to bear against the base flange 5 of the extension rail, and has its upper edge flanged or bent over, as at 14, to surround the upper edge of the base flange 5, the entire device being adapted to hug the rail preventing the accidental removal of the same therefrom. It will be 35 noted that each coupling or sleeve comprises two clamping or engaging parts or portions, one part embracing the head of the slide rail and the other engaging the base flange of said rail. The exact shape of the coupling or sleeve to accomplish these purposes is not material.

Each coupling or sleeve 8 is provided in the wall 13 with an eye 15, preferably formed by slitting the metal and bending outwardly 45 the portion thus provided. The eyes 15 are adapted to be engaged by the upstanding terminals 15^a of a connecting rod 16 which serves to hold the couplings or sleeves 8 in the proper spaced relation.

50 The couplings or sleeves 8 are adapted to extend substantially half way beyond the ends of the extension rails 3, and said sleeves are provided with spaced holes 17 a distance apart substantially equal to the width of a tie 2. The rails 3 are each provided with similar holes 18 formed in the webs 6 thereof and a distance from the ends of the same substantially equal to one-half the width of a tie 2, so that when the sleeve is in position on the end of the extension rail, the several holes may register and receive a pin 19 which may be dropped through the same and rest against the opposite sides of the tie 2, in order to prevent any longitudinal 65 movement of the sleeve along the tie.

When it is desired to elongate the extension, another pair of rails 20 similar to the rails 3 may be utilized, and these are secured in the sleeves in the same manner as before described, the said rails 3 and 20 serving to 70 carry the car or machine in proximity to the work.

From the foregoing it will be seen that a simple and cheaply manufactured holding device for mine rails has been provided, 75 which may be easily handled to extend the track, and which will serve to hold one or two pairs of extension rails in position with relation to the permanent track. It will be understood that the outer ends of the second 80 pair of rails 20 may be held in position upon another tie by suitably spiking the same.

What is claimed is:

1. A device for holding the slide rails of mine tracks, with the slide rails lying on 85 their sides, their base flanges assuming an inclined position and their heads engaging the webs of the permanent rails, comprising a sheet metal coupling or sleeve shaped to conform to the contour of the rails and having a part to clamp the head of the slide rails and another part to clamp the base flange of said slide rails.

2. Means for holding the slide rails of mine tracks, with the slide rails lying on 95 their sides and their heads engaging the webs of the permanent rails beneath the heads of the latter, comprising a pair of like couplings or sleeves each constructed to clamp respectively the heads and the base 100 flanges of the slide rails, each coupling being shaped to permit passage of the flange of the wheel of the mine car between those parts clamping the heads and base flanges aforesaid.

105 3. A device for holding the slide rails of mine tracks, comprising a pair of substantially identical couplings or sleeves shaped to conform to the contour of the rails so as to support the same at their outer ends while lying on their sides, with the inner ends of the slide rails fitting between and engaging the permanent rails of the track and constituting continuations thereof, said couplings each comprising a base portion having at 110 one side an upstanding wall with an inwardly-directed wall terminating in an inwardly-directed marginal flange, said walls and flange fitting and engaging the head of the slide rail, said base portion having at the other side an upstanding wall with its upper edge flanged to engage the upper edge of the base flange of the slide rail.

115 4. A device for holding slide rails for 125 mines, comprising a pair of substantially identical, oppositely disposed metallic couplings or sleeves adapted to partially surround and support the outer free ends of the slide rails while resting upon a tie, said 130

couplings being shaped to conform to the shape of the rails while lying on their sides, means for maintaining the couplings in spaced relation, and means for connecting the couplings to the tie to prevent longitudinal movement of the slide rails.

5. A holder for the slide rails of mine tracks, comprising a pair of substantially identical sheet metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and pins adapted to traverse registering openings formed in the sleeves and the ends of the slide rails, said pins bearing against the sides of the tie to prevent longitudinal movement of the slide rails, said sleeves being adapted to receive another pair of slide rails in their overhanging portions and to be locked thereto by a pair of the pins to further extend the track.

10 6. A holder for the slide rails of mine tracks, comprising a pair of substantially identical sheet metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and means to prevent longitudinal movement of the slide rails, said sleeves being adapted to receive another pair of slide rails in their overhanging portions and to be locked thereto by said means to further extend the track.

15 7. A holder for the slide rails of mine tracks, comprising a pair of substantially identical metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and means to prevent longitudinal movement of the slide rails, said sleeves being adapted to receive another pair of slide rails in their overhanging portions and to be locked thereto by said means to further extend the track.

20 8. A holder for the slide rails of mine tracks, comprising a pair of substantially identical metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and means to prevent longitudinal movement of the slide rails, said sleeves being adapted to receive another pair of slide rails in their overhanging portions and to be locked thereto by said means to further extend the track.

25 9. A holder for the slide rails of mine tracks, comprising a pair of substantially identical metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and means to prevent longitudinal movement of the slide rails, said sleeves being adapted to receive another pair of slide rails in their overhanging portions and to be locked thereto by said means to further extend the track.

30 10. A holder for the slide rails of mine tracks, comprising a pair of substantially identical metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and means to prevent longitudinal movement of the slide rails, said sleeves being adapted to receive another pair of slide rails in their overhanging portions and to be locked thereto by said means to further extend the track.

35 11. A holder for the slide rails of mine tracks, comprising a pair of substantially identical metal couplings or sleeves shaped to conform to the contour of the rails and to support the same at their outer ends while lying on their sides, with their inner ends between the permanent rails and constituting continuations thereof, said sleeves being adapted to rest upon and be secured to a tie and to overhang the ends of the slide rails while straddling the tie, eyes formed in the opposed faces of the couplings or sleeves, a connecting rod engaging the eyes and resting upon the tie, and means to prevent longitudinal movement of the slide rails, said sleeves being adapted to receive another pair of slide rails in their overhanging portions and to be locked thereto by said means to further extend the track.

tuting continuations thereof, said sleeves being adapted to rest upon and be secured to a tie and to overhang the ends of the slide rails while straddling the tie, and pins 40 adapted to traverse registering openings formed in the sleeves and the ends of the slide rails, said pins bearing against the sides of the tie to prevent longitudinal movement of the slide rails, said sleeves being 45 adapted to receive another pair of slide rails in their overhanging portions and to be locked thereto by a pair of the pins to further extend the track.

7. A holder for the slide rails of mine 50 tracks, comprising a pair of substantially identical metal couplings or sleeves shaped to conform to the contour of the rails and to support the same at their outer ends while lying on their sides, with their inner ends 55 between the permanent rails and constituting continuations thereof, said sleeves being adapted to rest upon and be secured to a tie and to overhang the ends of the slide rails while straddling the tie, eyes formed in the 60 opposed faces of the couplings or sleeves, a connecting rod engaging the eyes and resting upon the tie, and means to prevent longitudinal movement of the slide rails, said sleeves being adapted to receive another pair 65 of slide rails in their overhanging portions and to be locked thereto by said means to further extend the track.

In testimony that I claim the foregoing as my own, I have hereto affixed my signature. 70

JAMES EDWARD WILSON.
